To all whom it may concern:

Be it known that I, Robert S. Gentile, a citizen
of the United States, residing in New York city,
in the county of New York and State of New
York, have invented a new, original, and orna-
mental Design for a Textile Fabric, of which the
following is a specification, reference being had
to the accompanying drawing, forming a part
thereof.

The figure is a plan view of a textile fabric
showing my design.

I claim:

The ornamental design for a textile fabric, as
shown.

ROBERT S. GENTILE.
